[57] CLAIM

The ornamental design for a food tray, as shown and described.

DESCRIPTION

FIG. 1 is a top plan view of a food tray of a first embodiment of this invention;

FIG. 2 is a side elevation view thereof, the opposite side being identical;

FIG. 3 is a front elevation view thereof, the rear elevation view being identical;

FIG. 4 is a bottom plan view thereof;

FIG. 5 is a typical sectional view thereof;

FIG. 6 is a top plan view of a food tray of a second embodiment of the invention; and,

FIG. 7 is a side elevational view thereof, the other side being identical, the remaining views being the same as in FIGS. 3 and 5.

FIG. 1

FIG. 2

FIG. 3

FIG. 4

FIG. 5

FIG. 6

FIG. 7
